Herbert S. Chase, Flushing, N. Y., assignor to Bernard Cahn Co., Inc., New York, N. Y.

Application April 12, 1955, Serial No. 35,466

Term of patent 7 years

(Cl. D87—3)

The broken lines shown in Figures 1, 3 and 6 are for illustrative purposes only.

I claim:

The ornamental design for a map holder or similar article, substantially as shown and described.
